United States Patent Office

Des. 219,892

Patented Feb. 9, 1971

219,892

SUBMARINE

Edmund Stanley Martine, Savannah, Ga.
(2835 David Lane, Medford, Oreg. 97535)

Filed Oct. 24, 1969, Ser. No. 19,719

Term of patent 14 years

Int. Cl. D12—06

U.S. Cl. D71—1

FIG. 1

FIG. 2

FIG. 3

FIG. 1 is a side perspective view showing my new design for a submarine as viewed from the left;

FIG. 2 is an enlarged front elevational view thereof;

FIG. 3 is an enlarged rear elevational view thereof;

FIG. 4 is an enlarged side elevated view thereof as viewed from the right; and

FIG. 5 is an enlarged top plan view thereof.

I claim:

The ornamental design for a submarine, substantially as shown.
